UNITED STATES PATENT OFFICE.

JOHN E. LAING, OF DUBOIS, PENNSYLVANIA, ASSIGNOR OF ONE-HALF TO JOHN F. MITCHELL, OF BELLS LANDING, PENNSYLVANIA.

AUTOMATICALLY-OPERATED RAILWAY-SWITCH.

1,072,337.

Specification of Letters Patent.

Patented Sept. 2, 1913.

Application filed October 19, 1912. Serial No. 726,663.

To all whom it may concern:

Be it known that I, JOHN E. LAING, a citizen of the United States, residing at Dubois, in the county of Clearfield and State 5 of Pennsylvania, have invented certain new and useful Improvements in Automatically-Operated Railway-Switches, of which the following is a specification.

The invention relates to switches for rail- 10 ways and is particularly adapted to switches used in mining railways and has for its principal object the provision of a switch that is adapted to be operated by a runaway car that has become detached from the main 15 train so as to throw the car into a siding and off of the main line to prevent accident.

Another object of my invention is the provision of an improved operating means for switches comprising a catch adapted to be 20 operated by an arm mounted on the car to release the switch members to be actuated by a weight or its equivalent to connect the main line with a siding.

Another object of my invention is the provision of an arm pivotally mounted on each 25 end of the car in position to actuate the switch latch heretofore referred to, said arm being held in a raised position when the car is coupled and is released into operative position should the car become uncoupled, the 30 rearmost car of the train having the arm extending downwardly into operative position at all times.

My invention will be described in detail 35 hereinafter and illustrated in the accompanying drawings, in which,

Figure 1 is a side view in elevation of a railroad and a car mounted thereon showing my improved switch operating mechanism; Fig. 2, a top plan view showing the switch in position with the main line open; Fig. 3, a similar view showing the siding connected with the main line; Fig. 4, a longitudinal sectional view on the line 4—4 of Fig. 2; and Fig. 5, a cross section on the plane indicated by the line 5—5 of Fig. 2.

In the drawings similar reference characters will be used to designate corresponding parts in the several views.

50 In mine railroads, one of the dangers is the liability of one or more of the cars at the rear end of the train breaking away from the train and running wild through the mine, and where the trains closely follow 55 one another, it will be apparent that there

is grave danger of wrecks caused by these runaway cars. The purpose of my invention as heretofore stated, is to prevent the runaway cars from doing damage and to this end I locate sidings at suitable distances 60 apart on each incline within the mine to take care of such runaway cars and in the drawings I have illustrated one of these sidings with the switch operated mechanism.

The main line of my track indicated at 65 1 will have located at suitable distances switches consisting of the switch points 2, 3, that are normally in alinement with the main track 1 and the switch points 4 and 5 that connect with a suitable siding (not 70 shown), all of said switch points 2, 3, 4 and 5 being suitably pivoted at their terminals farthest removed from the track rails 1 by any suitable means (not shown) in the drawings. The switch points 2, 3, 4 and 5 75 adjacent to the track rails 1 are also pivoted to a cross bar 6 by means of bolts or other equivalents 7, this structure insuring the movement of the free ends of the switch points 2, 3, 4 and 5 simultaneously. 80

Pivotally secured to the switch points 2 by means of a bolt or rivet 8 is a plate 9 having its free end provided with a flexible member 10 that is trained around pulleys 11 and supports a weight 12 on its free terminal mounted within a suitable casing 13 arranged at the side of the track. It will be apparent that the weight 12 normally tends to move the switch points 2, 3, 4 and 5 so that the points 4 and 5 are in alinement 90 with the main track rails 1 to throw any car moving down the track into the siding heretofore referred to and to prevent this movement of the switch points 2, 3, 4 and 5, I provide a latching means comprising a 95 shaft 14 journaled on the plate 9 and having a laterally extending arm 15 that engages the inclined projection 16 on the tie 17 adjacent to the terminals of the switch points 2, 3, 4 and 5. 100

In order that the latch arm 15 may be raised from engagement with the projection 16 to release the switch to the influence of the weight 12 by means of an apparatus secured to the car which will be hereinafter 105 more particularly described, I provide a bar 18 that is arranged longitudinally of the track and pivotally secured at one of its terminals to a crank arm 19 extending from the shaft 14 and having its other terminal 110

pivotedly connected to a crank arm 20 on a shaft 21 journaled on a tie 22 at a distance from the switch. The terminals of the bar 18 are provided with slots 23 to receive the pivotal connections heretofore described to permit a slight transverse movement of the terminal of the bar 18 connected with the crank arm 19 when the switch is actuated by the weight as heretofore described, so that the bar 18 assumes the position as shown in Fig. 3.

In Figs. 1 and 2, I have shown a car mounted on the main line track 1, said car being assumed to be the rearmost car of a train going up the incline as shown in Fig. 1 and said car designated 24 is provided with means to engage the bar 18 to rotate the shaft 14 and lift the latch arm 15 from engagement with the projection 16 to permit the switch to be actuated to throw the car on the siding should it be uncoupled or break away from the train, it being necessary to provide each of the cars of the train with the improvements on its two ends so that no matter in which direction the car is going there will be means for actuating the switch on the rearmost car and properly positioned to actuate the switch.

The means for actuating the switch consists in providing the bumper 25 on one side of the coupling with a plate 26 by means of a suitable bolt 27 having rearwardly extending ears 28 between which is suitably pivoted an arm 29 that will normally hang down in the position shown in Fig. 1 so that should the car 24 be disconnected from the train in any manner and run down the track 1, the arm 29 will engage the bar 18 and by moving it toward the shaft 14 will cause said shaft to rock and lift the latch arm 15 from engagement with the projection 16 and open the siding (not shown) to the main line as heretofore described.

Having thus described the invention what is claimed is:—

1. In combination with the main line of a railroad, a switch having switch points, means to hold said switch normally in position to keep the main line open, means normally tending to move the switch to connect siding rails with the main line, and means to release the holding means aforesaid to actuate the switch, including a connection for said switch points, a bar disposed longitudinally of the main line between the rails thereof, a shaft mounted for rotation on said connection, one terminal of said bar secured intermediate the ends of said shaft, and the other terminal of said bar reciprocatingly mounted above said rails.

2. In combination with the main line of a railroad, a switch comprising switch points pivotally secured, two of said switch points being in alinement with the main line and normally in position to retain said main line

in an open position, a plate operatively secured to said first mentioned switch points having one of its terminals extending beyond the outer edge of one of the rails of said main line, the other of said switch points being connected with the siding, a latching means to hold the switch in position to retain the main line in its open position, means normally tending to move the switch points to connect the siding with the main line, including a weight operatively secured to the extended terminal of said plate, a bar extending longitudinally of the main line between and above the rails thereof and operatively connected with the latch, said bar being adapted to be engaged by a projection on a car moving on the main line to release the latch and permit the switch to be actuated to connect the siding with the main line.

3. In a switch actuating mechanism, in combination with main line rails, a switch comprising switch points connected with the main line and with a siding, a plate operatively secured to said switch points, a weight operatively secured to said plate and normally tending to move the switch to connect the siding and switch points with the main line, a shaft journaled on said plate, a latch arm projecting from said shaft and adapted to lock the switch against actuation by said weight to hold the main line switch points in alinement with the main line, and means adapted to be actuated by a car moving on the main line to release said latch and the plate to the influence of said weight.

4. In a switch actuating mechanism, in combination with main line rails, a switch comprising switch points connected with the main line and with a siding, a plate operatively secured to said switch points, a weight operatively secured to said plate and normally tending to move the switch to connect the siding and switch points with the main line, a shaft journaled on said plate, a latch arm projecting from said shaft and adapted to lock the switch against actuation by said weight to hold the main line switch points in alinement with the main line, a bar extended longitudinally of the main line and operatively connected with said shaft, said bar being adapted to be engaged by a projection on a car moving on the main line to lift said latch and release the plate to the influence of the weight aforesaid.

5. In a switch actuating mechanism, in combination with main line rails, a switch comprising switch points connected with the main line and with a siding, a plate operatively secured to said switch points, a weight operatively secured to said plate and normally tending to move the switch to connect the siding and switch points with the main line, a shaft journaled on said plate, a latch arm projecting from said shaft and adapted to lock the switch against actuation by said

weight to hold the main line switch points in alinement with the main line, a crank arm secured to said shaft, a shaft journaled at a distance from the switch and provided with a crank arm, a bar arranged longitudinally of the main line and pivotally engaging said crank arms, said bar being adapted to be engaged by a projection on a car moving on the main line to actuate said shaft and to

lift the latch and release the plate to the 10 influence of the weight aforesaid.

In testimony whereof I affix my signature in presence of two witnesses.

JOHN E. LAING.
